Primary Examiner — Rebecca Tsehay

(57) **CLAIM**

The ornamental design for an electronic cigarette atomizer as shown and described.

DESCRIPTION

1. Electronic cigarette atomizer

1.1: Perspective

1.2: Front

1.3: Back

1.4: Top

1.5: Bottom

1.6: Left

1.7: Right

The broken lines in the drawings depict portions of the electronic cigarette atomizer that form no part of the claimed design.
